UNITED STATES PATENT OFFICE.

BLOOMFIELD BROWER, OF NEW YORK, N. Y.

DESIGN FOR AN INKSTAND.

Specification forming part of Design No. **6,878**, dated September 9, 1873; application filed August 9, 1873.
[Term of Patent $3\frac{1}{2}$ years.]

To all whom it may concern:

Be it known that I, BLOOMFIELD BROWER, of the city of New York, in the State of New York, have invented a Design for an Inkstand, of which the following is a specification:

The nature of my design is fully represented in the accompanying photographic illustration, to which reference is made.

A represents the base or foot plate of the inkstand. The outer edges around the top of said plate A are ornamented by projecting hanging serrated points a. On the top of the plate prismatic points n n are arranged in two rows opposite each other, and corresponding in size and their distances apart with each

other, leaving suitable recesses between said prismatic points.

The distinctive character of my design is found in the serrated points around the upper edge of the base-plate and the prismatic points on the top of the plate.

What I claim as my invention is—

A design for an inkstand, arranged and ornamented substantially in the manner above described.

BLOOMFIELD BROWER.
